[57] CLAIM

The ornamental design for a standing lamp, as shown and described.

DESCRIPTION

FIG. 1 is a front view of a standing lamp base showing my new design, the rear view being identical;

FIG. 2 is a bottom view thereof on a reduced scale;

FIG. 3 is a side view thereof;

FIG. 4 is a front view of a second embodiment of my new design, the rear being identical;

FIG. 5 is a top view thereof; and,

FIG. 6 is a side view thereof.

The shade is shown in broken lines for illustrative purposes only and forms no part of the claimed design.

FIG. 3

FIG. 2

FIG. 1

FIG.4

FIG.5

FIG. 6
